ELECTRON DISCHARGE DEVICE

Harry Kenneth Ishler, Emporium, Pa., assignor to
 Sylvania Electric Products Inc., Emporium, Pa.,
 a corporation of Massachusetts

Application May 19, 1943, Serial No. 487,561

2 Claims. (Cl. 250—27.5)

This invention relates to electron discharge devices and in particular to the design of electron tube units of light weight and small dimensions.

Most of the various sizes and shapes of radio receiving tube types usual on the market about ten years ago have now been replaced by a single shape and size, considerably smaller than the average size formerly believed necessary for good performance. This form to which the older receiving tube types have converged is substantially that of a standard called lock-in tube. No serious demand for a smaller radio receiving tube seems to exist at the present time, and a proposed further reduction of size apparently did not correspond to any existing demand.

An actual need for a considerably smaller electron discharge tube existed, however, in applications other than radio broadcast reception. Representative of this demand are hearing aid sets, in which a reduction of the weight and size of amplifier tubes to the absolute minimum obtainable for the present status of the art is of immediate practical importance.

The development of hearing aid tubes has therefore led to a further improvement of the art connected with a considerable reduction of tube size, so that it is now possible to manufacture these exceedingly small tubes with practically no sensitivity against mechanical shock or handling.

Accordingly, a principal object of the invention relates to the reduction of the weight of the electrodes used in extremely small electron discharge tubes.

A feature of the invention relates to a small size electron discharge tube in which the heat radiation from the anode is increased, compared to the heat radiation obtained from a larger size anode in a tube of similar dimensions.

Another object is to provide a plate construction which can be formed by simple punching and shaping operations on a single sheet of metal.

According to another object of the invention, means are provided to reduce the output capacity of a small filamentary electron discharge tube with a single strand filamentary cathode.

Another principal object is to provide a plate construction for electron tubes which facilitates examination of the electrode assembly during or after manufacture, and the ancillary object of expediting the outgassing of the metal parts.

According to still another object of the invention, the ratio of the interelectrode capacity between filament and control grid to that between filament and anode can be adjusted to any desired value within limits.

A feature of the invention relates to an extremely small electron discharge tube having a minimum variation of input capacity over a wide frequency band.

Another feature of the invention relates to a

new method which permits the reduction of certain interelectrode capacities of an electron discharge tube without increasing the size of the bulb or providing separate lead-in seals through different parts of the envelope.

A still further feature of the invention relates to an electron discharge tube in which all the lead-in conductors are brought out through a single header or stem, which is of extremely small dimensions, which has the correct interelectrode capacities for certain circuit applications, and which is very light in weight but does not change its important electrical characteristics when subjected to extremely rough handling or shock.

One of the most important objects of the invention is the combining of all the above-noted features, each single one of which is, in the usual tube constructions obtained at the expense of some of the others. For example, the reduction of interelectrode capacitances may be achieved by the introduction of additional shielding electrodes (e. g., screen grids), which however, increase the weight and eventually the size of the tube. Or it may be obtained by increasing the size of the envelope and carrying the lead-in conductors through widely remote parts of the envelope. This not only changes the tube size but it also leads to undesirable sealing-in processes and may not be consonant with existing circuit requirements.

Usually a reduction of the mass of the electrodes results in a decrease of the mechanical ruggedness of the tube, and a reduction of its ability to radiate large quantities of heat at low temperature. According to the invention, means are provided whereby the mass of an electrode is decreased while its heat dissipation ability during actual use, is simultaneously increased. Ordinarily, an increase of heat radiation surface of an electrode results in an increased size and weight of this electrode.

According to the invention, all these difficulties are avoided by a novel method of mounting and a change of shape of some of the electrodes, which permits a simultaneous achievement of these various ends without any sacrifice of space or simplicity of the various other steps necessary for manufacturing a finished tube.

The invention will now be described in connection with the drawing, in which,

Fig. 1 is a cross-sectional view of a triode mount with filamentary cathode, built for high mechanical sturdiness, and provided with large radiating surface of the anode, corresponding to prior designs.

Fig. 2 is a side view of the same triode mount.

Fig. 3 shows a cross-section through a similar triode, but improved according to the invention.

Fig. 4 gives a side view of the mount of Fig.

Fig. 5 is an elevational view of the plate shown in Figs. 3 and 4.

The triode mount illustrated in Figs. 1 and 2, consists of a header or stem 1 through which are sealed lead-in connections 2, 3, 4, 5, etc. The plate 6 is supported by four plate support wires 7, 8, 9, 10, attached in any well-known manner to the mount spacers 11 and 12, preferably made of mica sheets. Also attached to these upper and lower mount spacers are grid supports 13 and 14, on which is wound the grid wire 15, also in a manner well-known in the art. Filament 16 is threaded through central holes in the mount spacers, and the lower end of filament 16 is connected to one of the lead-in wires 3. The upper end of the filament is held taut by any convenient filament tension spring 17, one end of which is welded to filament tension spring support 18, by means of a filament tab 19.

The filament voltage may be applied to the filament 16 at the filament lead 3 and the filament spring support lead 20 as shown in the figure. It is of course understood that grid and plate of the tube are connected to some conveniently located lead-in conductors (not shown in the figure) in the header 1.

Filament and grid are completely surrounded by a box-like anode structure, whereby the grid structure is electrostatically shielded by the anode from the filament tension spring support. The plate-to-grid capacity is comparatively large, due to the fact that the grid is completely surrounded by the anode. This construction is very sturdy because of the four plate supports and the sidewalls 21 and 22, and end walls 23, 24, of the plate box, which provides great stiffness to the plate structure. The plate walls are solid surfaces and the continuations 25, 26, 27 and 28 of the active plate walls 21 and 22, increase the radiation surface of the plate, so as to permit a greater heat dissipation.

In Figs. 3-5 is shown the new design according to the invention, in which the plate shape and the position of the filament tension support are so modified as to result in a lowered plate to grid capacity, and an increased inherent capacity between the filament tension spring support 18, and the grid 15, while the characteristics of the electron discharge space are not changed compared with the design of Fig. 1. It should be noted that the large inherent capacity resulting from the closeness of filament tension spring support 18 (in Fig. 1) to the end wall 23 of the plate is completely eliminated in the construction shown in Figs. 3 and 4. The distance between 18 and the plate wings 29 and 30 in Fig. 3, reduces the output capacity very appreciably.

Inspection of Figs. 1 and 3 also shows directly the way in which, according to the invention, the low grid-to-filament capacity of Fig. 1 (substantially due to the shielding effect of the plate when located between filament tension spring support 18 and grid 15) is increased in Fig. 3 by removing the shielding end wall 23 of the plate, and thus permitting some of the electric lines of force from the support 18 to end directly on the grid 15, without interception.

Furthermore, removal of this plate end wall in Figs. 3-5, decreases the plate-to-grid capacity, as compared with the closed box construction of Fig. 1.

Finally, it is obvious that in the construction of Figs. 3-5, it is always possible to adjust the

ratio of the effective interelectrode capacities between filament and grid on the one hand to that between filament and plate on the other hand, merely by shifting the position of filament support 18 along the dotted line arrows (Fig. 3).

The cooling of the plate is made more effective by bending the plate wings 29 and 30 outward and away from the discharge space much closer to the area of maximum electron dissipation near the grid laterals, as indicated by the full-line arrows which suggest the discharge path. As may be seen more clearly from Figs. 4 and 5, the weight of the plate is appreciably reduced by openings in the wings and rib of the anode, which are not electrically active in this design.

It should be noted that the plate electrode in Figs. 3 and 4, is supported by only three plate supports 31, 32 and 33, as compared to the four plate supports needed in the prior design of Figs. 1 and 2. One might expect at first sight that the support has been weakened by the omission of one of the previously used plate supports. This is, however, not the case, as will be easily understood from the following consideration. The total weight of the anode of Figs. 3-5 is smaller than that of the closed box-anode of Figs. 1 and 2 for two reasons. The full length of the metal strip needed for forming the anode is shorter than that needed for forming the box-plate of Fig. 1. Furthermore, some of the metal stock of the new plate is eliminated by punching out holes from the ribs and wings, as mentioned before in connection with Figs. 4 and 5.

In one type of tube of this kind actually being built, the total weight of the anode has been reduced to about 60% of its original weight while preserving the other desirable characteristics of the prior plate. Accordingly, the load per plate support in the new construction is reduced to only 80% of the weight which each one of the four plate supports had to carry in the older design, even though the number of plate supports has been reduced. It will be clear that the invention is not limited in spirit or scope to the particular embodiment disclosed, and that various changes and modifications can be made therein as will be apparent after considering the foregoing description and the appended claims.

What I claim is:

1. An electrode for electron discharge tubes, comprising a metal strip bent to form a trough-like shape in transverse section, the edges of the trough being bent back and forming diverging wings, the main trough-like portion being unperforated to act as an electron receiving electrode and said bent-back wings being perforated, and means to support the electrode adjacent the edges of said wings and adjacent the base of said trough, said supporting means being positioned in triangular array.

2. A tube mount comprising a header carrying a plurality of electrode support rods, a plate electrode supported on three of said rods arranged in triangular array, said plate being of metal bent back upon itself to form a constricted channel to receive one of said rods and an enlarged trough-like section serving as an electron chamber, the edges of said trough-like section being bent back and outwardly diverging and attached to respective support rods.

HARRY KENNETH ISHLER.
